(57) **CLAIM**

The ornamental design for a motorcycle passenger arm rest, as shown and described.

DESCRIPTION

FIG. 1 is a perspective view of the motorcycle passenger arm rest of the present invention.

FIG. 2 is a right side elevation view thereof.

FIG. 3 is a left side elevation view thereof.

FIG. 4 is a top view thereof.

FIG. 5 is a bottom view thereof.

FIG. 6 is a front elevation thereof; and,

FIG. 7 is a rear elevation thereof.

The motorcycle passenger arm rest portions shown in broken lines form no part of the claimed design.
